UNITED STATES PATENT OFFICE

134,477

DESIGN FOR A ROOF VENTILATOR

Freeland H. Leslie, Chicago, Ill.

Application October 25, 1941, Serial No. 103,892

Term of patent 14 years

To all whom it may concern:

Be it known that I, Freeland H. Leslie, a citizen of the United States, resident of Chicago, county of Cook, and State of Illinois, have invented a new, original, and ornamental Design for a Roof Ventilator, of which the following is a specification, reference being had to the accompanying drawing, forming part thereof.

Figure 1 is a perspective view of a roof ventilator showing my new design; and

Figure 2 is a front elevational view thereof.

The roof ventilator of my design is characterized by the front wall portion being in acute angular relation to the top portion of the ventilator.

I claim:

The ornamental design for a roof ventilator, substantially as shown and described.

FREELAND H. LESLIE.
